SPACING FASTENER

Application filed June 2, 1928. Serial No. 282,431.

This invention relates to fasteners, and aims, among other objects, to provide an improved spacing fastener well adapted for use in securing reenforcing wire to sheathing 5 to hold the wire properly and uniformly spaced from the sheathing whereby it will be embedded in plaster or stucco applied to the sheathing.

In the accompanying drawing:—
10 Fig. 1 is a fragmentary side elevation showing chicken wire applied to sheathing by means of the preferred form of fasteners;

Fig. 2 is a fragmentary sectional view taken on the line 2—2 of Fig. 1;
15 Fig. 3 is a side elevation, partly in section, and on an enlarged scale, of the fastener shown in Figs. 1 and 2; and

Fig. 4 is a bottom plan view on an enlarged scale of the fastener shown in Fig. 3.

20 Heretofore, various spacing fasteners for securing expanded metal lath and reenforcing wire have been proposed, but all of them which have been available to the trade are open to some very serious objections. Among 25 these objections are, the necessity to assemble a furring nail with a metal spacer member, or the objectionable jagged edges presented by those which are already assembled, making them very difficult to handle. Further, 30 the assembled fasteners often permit nail points to project beyond the spacers so that they will cut the building paper which is applied to the sheathing preparatory to putting on the plaster or stucco and such cut 35 places will invariably permit moisture from the plaster to penetrate the paper and rust out the nail. Moreover, most of the metal fasteners are open to the very serious objection that they do not space the reenforcing 40 wire or lathing uniformly from the sheathing so that it will be embedded at about the center of the plaster or stucco. This invention aims to provide a relatively simple fastener assembly that can be very easily and 45 quickly applied and that is not subject to the foregoing objectionable features.

Referring to Figs. 2, 3 and 4, the preferred form of fastener is shown as comprising an ordinary galvanized furring nail 10 having 50 an enlarged head 11 and a tapered point 12

which penetrates the head 13 of a spacer button 14 having an annular flange 15 adapted to abut the sheathing or the outer surface of the paper.

The button member 14 is preferably 55 formed by die stamping operations and is conveniently made of some relatively soft sheet metal such as brass, bronze or the like so that it is practically rustproof, and, further, so that it may be easily penetrated by 60 the point of one of the nails. Moreover, the thickness of the button is such that it will properly space the reenforcing wire from the sheathing, it being understood that it may be made of various thicknesses depending 65 upon the particular requirements.

To avoid the necessity for a carpenter to assemble each cap and nail on the job, they are pre-assembled so that they are ready to 70 be applied very quickly and so that the carpenter may take them out of his pocket, one at a time, and slip the buttons under one or more strands of the taut wire 16 where they are held ready to be struck with a hammer to clamp the wire between the nail heads 75 and the button heads.

The nails and the buttons are shown as being assembled by driving the nail points through the button heads so that the points of the nails are about flush with the bases of the buttons, the tapered ends of the nails being somewhat shorter, so that the broken out projections formed on the button will engage the shank of the nail and hold the 85 button on the nail by friction.

If desired, the buttons may be first formed with a small hole into which the point of the nail is inserted, thus making it easier to drive the nail into the button. Either 90 method may be accomplished by using suitable dies so that the cost of manufacture will be exceedingly small.

Referring to Figs. 1, 2 and 3, it will be seen that the heads of the furring nails and the heads of the buttons are of substantially 95 the same diameter, so that they present relatively wide gripping surfaces. When the nails are driven home to grip the wire strands against the button heads, the buttons are 100 somewhat deformed by the wire and this

prevents the wire from pulling out when the plaster or stucco is applied. Moreover, the cups provide an air space between the building paper and the button heads to permit 5 expansion and contraction, without cracking the plaster or stucco after it has set. However, the strength of the buttons is such that an ordinary hammer blow will not crush them and affect the proper spacing of the 10 stretched wire from the sheathing. Also, the shanks of the nails will seal the openings in the heads of the buttons so that no moisture can penetrate them and rust out the 15 nails in the hollow portions or air spaces of the buttons.

From the foregoing description, it will be apparent that the fasteners may be made very economically and are assembled ready for instant application. A carpenter can 20 save about one-third of his time by using them instead of the nails and spacers which have to be assembled on the job or other types of assembled fasteners which present jagged or pointed portions and which are 25 apt to stick together in his pocket. By reason of the buttons being securely fastened on the nails so that the points of the nails come about flush with the bases of the buttons, they may be pushed between the strands of the 30 stretched wire and the building paper without tearing the paper. The buttons provide substantial supports for the wire and will withstand the tremendous strains imparted to them by the weight of the plaster or stucco. 35 Another advantage resides in the fact that the punctured opening in the cap of the button is completely sealed by the nail. Further the button is not subject to destructive expansion and contraction which would crack 40 the plaster or stucco.

Obviously, the present invention is not restricted to the particular embodiment thereof herein shown and described. Moreover, it is not indispensable that all the features 45 of the invention be used conjointly, since they may be employed advantageously in various combinations and sub-combinations.

What is claimed is:—

1. A spacing fastener of the class described comprising, in combination, a sheet metal, substantially cup-shaped button member of relatively soft metal presenting an annular base flange and a relatively large head portion; and a furring nail penetrating the head 50 portion of the button, and co-operating with the punctured projections of the button head to hold the button and nail assembled so that the point of the nail does not project beyond the plane of the base of the button member, whereby the button member may be pushed under the strands of a reinforcing wire and the nail point will not tear the 55 building paper on the sheathing.
2. A non-rusting metal spacer for pre-assembled fasteners for wire sheathing and the 60

like comprising, in combination, a hollow body having a continuous annular base flange, continuous frusto-conical walls, and a flat head to serve as an anvil; said head having a hole punched therein of slightly 70 smaller diameter than the shank of a suitable furring nail, so that when the furring nail is forced through the hole, it may be firmly held by friction with its point substantially flush with the plane of the base flange, the 75 space enclosed by the frusto-conical walls constituting a water-tight air pocket around the shank.

3. A pre-assembled fastener for wire sheathing and the like comprising a non-rusting, relatively soft metal body which is 80 cup-like in form, with an annular, continuous base flange, continuous frusto-conical walls and a flat top to serve as an anvil; a furring nail driven centrally through said 85 top and held to the body by friction, with its point inside the body; the top of said metal body being of substantially the same dimensions as the head of the nail; the head of said nail, when driven into a support, being practically in contact with the top of the body, and said top being then deformed sufficiently to grip the wire of the sheathing.

In testimony, that I claim the foregoing as my own, I have hereto affixed my signature.

WM. H. F. ZIEDRICH.
